UNITED STATES PATENT OFFICE.

OLIVER THORN, OF LONDON, ENGLAND.

DESIGN FOR A GOLF-CLUB-CARRYING ATTACHMENT FOR CYCLES.

SPECIFICATION forming part of Design No. 33,689, dated December 11, 1900.

Application filed November 2, 1900. Serial No. 35,292. Term of patent 7 years.

To all whom it may concern:

Be it known that I, OLIVER THORN, a subject of the Queen of Great Britain and Ireland, residing at London, England, (and whose post-office address is No. 19 Great Portland Street, Oxford street, London, England,) have invented and produced a new and original Design for a Golf-Club-Carrying Attachment for Cycles, of which the following is a specification.

My invention relates to a new and original design for a golf-club-carrying attachment for cycles; and the design consists of the essential characteristics hereinafter referred to, and shown in the accompanying drawings.

In the accompanying drawings, Figure 1 is a side elevation. Fig. 2 is a view of Fig. 1 looking in the direction of the arrow 2. Fig. 3 is a view looking in the direction of the arrow 3, Fig. 1.

a represents the straight central portion of a flat clip, and *a'* *a²* the two flat end portions bent to extend outwardly at right angles to said central portion.

b represents a loop, one of said loops being 25 securely fastened to and extending in a longitudinal direction in respect to each of said end portions *a'* *a²*.

c represents a bent U-shaped clip, the ends of which are somewhat contracted, said clip 30 being secured to the said central portion *a*.

The essential features of the design are the flat member *a*, with turned-up portions *a'* and *a²*, with the metal loops or strap-holes *b* *b* on the said end portions *a'* and *a²* and located 35 near the end of each said end portion, and the clip *c*.

What I claim is—

The design for a golf-club-carrying attachment for cycles substantially as herein shown 40 and described.

In witness whereof I have hereunto set my hand in presence of two witnesses.

OLIVER THORN.
